UNITED STATES PATENT OFFICE.

GABRIEL A. BOBRICK, OF LOS ANGELES, CALIFORNIA, ASSIGNOR, BY MESNE ASSIGNMENTS, TO UNITED STATES LIQUID AIR & OXYGEN COMPANY, OF LOS ANGELES, CALIFORNIA, A CORPORATION OF CALIFORNIA.

APPARATUS FOR LIQUEFACTION OF GASES.

No. 924,137.

Specification of Letters Patent.

Patented June 8, 1909.

Application filed December 13, 1904. Serial No. 236,741.

To all whom it may concern:

Be it known that I, GABRIEL A. BOBRICK, a citizen of the United States, residing at Los Angeles, in the county of Los Angeles 5 and State of California, have invented new and useful Improvements in Apparatus for the Liquefaction of Gases, of which the following is a specification.

The primary object of my invention is to 10 provide a system and apparatus by which gases and mixtures of gases having a low critical temperature below zero F., or a high critical pressure, above 150 pounds to the square inch, or both, such as oxygen, nitrogen, air, etc., can be liquefied in large quantities at a reasonable cost; and by which system the present great cost of installing machinery and apparatus suitable for compressing gases to exceedingly high pressure 15 20 can be reduced to a minimum; also the necessity of providing exceedingly strong apparatus and heavy or thick-walled temperature interchanging coils which are not only costly but detrimental to the proper interchange of temperature, can be obviated.

Another object of my invention is to effect 25 the necessary lowering in temperature by adiabatic expansion means which have a much greater thermal efficiency than the free expansion means now generally employed in the manufacture of liquid air, etc.

Another object of my invention is to provide means by which that portion of the gases which assumes the liquid state and such admixtures as carbon - dioxid, for instance, which assumes the solid state in the pipes, channels or chambers above the expansion devices, can be separated and automatically removed from the unliquefied gases and therefore 30 35 40 by prevented from passing into or through the expansion devices.

Another object of my invention is to provide means by which the process of manufacturing liquefied gases, and particularly liquid air, can be made continuous, obviating the necessity of stopping at intervals for the sole purpose of thawing out and removing from the pipes of the liquefier the frozen particles of moisture and lubricating oil carried thereinto by the compressed air, or oil alone in the case of compressed gases free from moisture, etc.

A further object of my invention is to provide means by which a part of the air or gas

can be used more than once in regenerative cooling, by a succession of expansion and temperature-interchanging devices, thereby increasing the capacity and efficiency of the system.

A further object of my invention is to provide means by which all or part of the heat generated in the process of compressing the air or gas can be utilized for increasing the efficiency of the power cylinder of the internal combustion engine.

To simplify the specification I will describe a plant for the manufacture of liquid air, but it is to be understood that the apparatus used for liquefying air or any gas within the range of its capabilities, and that the use in this specification of the terms "air" and "gas" is not intended as any limitation of the invention.

Certain mechanical expressions of the inventive idea involved are shown in the accompanying drawings, which are designed merely as illustrations to assist in the description of the invention, and not as defining the limits thereof.

The accompanying drawings illustrate the invention, and referring to the same:—Figure 1 is an elevation somewhat diagrammatic of the complete system of apparatus, some of the parts being shown in section. Fig. 2 is a vertical section of the liquefier proper. Figs. 3 and 4 are detail sections of a modified form of separator. Fig. 5 is a view similar to Fig. 1 showing a different embodiment of the invention. Fig. 6 is a vertical section of the liquefier shown in Fig. 5. Fig. 7 is a diagrammatic representation of a system adapted for large plants.

Referring to Fig. 1, an air compressor is designated in a general way at 1 comprising power-cylinder 2, preferably an internal combustion engine, and compression cylinders 3 and 4, with intercooler 7, all arranged in the usual manner. The cylinders are water-jacketed and water supply is circulated through such jackets and through the intercooler, and discharged by pipe connections 8. It will be understood that the number of stages in the compressor will depend on the pressure used. From the cylinder 4 the compressed air is led by a pipe 9 to an oil and moisture separator 10, whence it passes by a pipe 11 to a cooler or temperature-interchanger 12 for absorbing the heat remaining

from final compression. Said cooler is preferably so constructed as to abstract this heat without recourse to cooling water or any cooling or heat-abstracting agent or medium other than air. It will be understood that for this purpose a more extended surface will be necessary than is required with a cooler using water as a heat-absorbing medium, and since every internal-combustion engine requires air for producing the explosive mixture, and since the higher the temperature of the air within certain practical limits the greater is the efficiency of said engine, I prefer to connect the temperature-interchanger 12 to the intake-pipe 13 of the cylinder 2, said temperature-interchanger 12 being of any suitable pattern, made in a cylindrical or any other form. The pipe 15 carrying the compressed air to be cooled, may be made in the form of a coil and located within a casing 14. The air for the internal-combustion cylinder is taken from a suitable place through pipe 16. It may be observed that the compressed air to be cooled flows in a direction opposite to that of the air to be warmed for the internal-combustion cylinder. An interchange of temperature takes place, and the compressed air upon leaving the temperature-interchanger is of about the same temperature as the atmosphere. This temperature-interchanger 12 thus serves a double purpose, the heat of compression being abstracted from the compressed air at the same time that the air for the power-cylinder 2 is being warmed. The cost of cooling water is saved, and the efficiency of the internal-combustion engine is increased. It is to be understood that if the power necessary for driving the compressor is derived from any other source than that of an internal-combustion engine directly connected to said compressor then said temperature-interchanger may be connected to the intake-air-pipe of any internal-combustion engine located on the premises or outside within a reasonable distance from the compressor or instead of the temperature-interchanger shown, any other cooler, such as an ordinary water-cooler, may be used. Part of the moisture and oil contained in the compressed air will condense in the coil 15, and will flow by gravity back into separator or trap 10 from which it may be removed from time to time through valve or cock 33. From the temperature-interchanger 12 the air passes by the pipe 17 into trap 24, thence into the counter-current apparatus called the forecoolers associated with the liquefier proper.

In order to perform the cooling action in this apparatus in the most efficient and convenient manner I find it desirable to divide such apparatus into a plurality of sections which will successively reduce the temperature of the air in the following manner:—

65 The first section indicated at 18 serves to re-

duce gradually the temperature of the compressed air to a stage approaching the freezing or solidifying point of water or aqueous vapors contained therein. The second section indicated at 19 serves to further reduce 70 the temperature of such compressed air to a point below the freezing or solidifying point aforesaid; while the third section, indicated at 20, serves to still further reduce the temperature of the compressed air to a point at 75 which it is adapted to enter the liquefier proper, practically free from moisture and vaporized oil. The first section 18 is desirably constructed with multiple tubes or conduits 22 each of comparatively small diameter, thereby providing a maximum heat-transferring effect between the gas flowing in these conduits and the surrounding medium. The outer envelop or conduit 21 surrounds these multiple tubes 22 and serves for the 80 passage of a return current of cool air, as hereinafter described. Headers 23 are provided for these multiple pipes 22. Inasmuch as the compressed air is cooled in this section 18 to approximately the freezing point of 85 water, it follows that there is no possibility of deposition of ice or snow in the pipes thereof, and therefore the latter may be made of comparatively small diameter without interfering with their regular and continuous operation. The greater part of the volatilized oil is removed from the air in this section and collected in traps 24 which are placed at the lowermost points thereof to enable the oil and water to collect and be 90 drawn off from time to time through valves or cocks 33. The next section 19 carries the refrigeration beyond the freezing point of water, and it is, therefore, not desirable to provide such section with small pipes similar 95 to those of section 18 as the deposition of ice and snow therein would soon clog the pipes and interfere with the continuous operation, although in large plants comparatively large pipes arranged in multiples may be used. 100 The internal pipe 26 of section 19 is, therefore, preferably a single conduit of relatively large diameter so as to allow deposition of ice and snow on its inner walls without interfering with the free passage of compressed 105 air therethrough. It will be understood that in the regular operation of the apparatus a considerably reduced amount of the aqueous vapor and oil will be contained in the compressed air when it reaches this section, so that only a comparatively very thin coating of ice and snow will form on the inside walls of pipes 26, and part of this may be blown out from time to time during the operation of the plant by opening the valves 33 110 of the traps 28 which are located at the lowermost points of this section.

27 designates the outer pipe or return current conduit of section 19.

Section 20 is shown as similar in construc-

130

tion to section 19, having a single conduit 30 of relatively large cross-sectional area and an external or return current conduit 31, traps 32 and blow-off cocks 33 located at the lower-
 5 most points of the internal conduit. From section 20 the compressed air passes by connections 34 and valve 35 to the liquefier proper 36. In regular operation the air has been cooled by the time it reaches the lique-
 10 fier to such a point that it is practically, or as near as it possibly can be done in practice, free from aqueous vapor and oil, and has also been relieved of part of its carbon-dioxid. It is, therefore, practicable to construct the
 15 internal conduit of the liquefier with multiple pipes or conduits 37 of relatively small diameter for the passage of the compressed air, thereby obtaining the result above set forth of increased heat-transmitting power.
 20 At the lower end the pipes or conduit 37 terminate in a header 38 which is connected directly or by pipe 39 to a separator 40 from which connection 41 leads to a trap 42, and connection 51 to an expansion device preferably a thermo-dynamic engine 53 in which the compressed air is made to expand adiabatically or nearly so. My reasons for employing an adiabatic expansion device for the free expansion means, now in general use,
 25 30 in the manufacture of liquid air and other liquefied gases having low critical temperatures, are these:— It is known that air upon free expansion from a space maintained at a higher pressure into a space maintained at a lower pressure, drops in temperature, and that the drop in temperature due to internal work performed by such expansion, is expressed in the formula
 35

$$40 \quad d = 0.276 (p_1 - p) \left(\frac{273}{t_1} \right)^2,$$

in which $p_1 - p$ represents the difference in pressure of the air before and after expansion, in atmospheres, and t_1 the absolute temperature of the air immediately before expansion, in degrees C. It will be observed that according to the above formula the greater the difference in pressure ($p_1 - p$), or the lower the temperature (t_1) of the air before expansion, the greater is the fall in temperature; and theoretically, if $p_1 - p =$ one atmosphere, then

$$55 \quad \begin{aligned} d &= 0.44 \text{ deg. F. if } t_1 = 62 \text{ deg. F.} \\ d &= 0.50 \text{ " F. if } t_1 = 32 \text{ " F.} \\ d &= 0.58 \text{ " F. if } t_1 = 0 \text{ " F.} \\ d &= 0.92 \text{ " F. if } t_1 = 100 \text{ " below zero F.} \\ d &= 1.78 \text{ " F. if } t_1 = 200 \text{ " " F.} \\ d &= 2.09 \text{ " F. if } t_1 = 220 \text{ " " F.} \end{aligned}$$

(the critical temperature of air).

On the other hand, if the air is expanded
 60 adiabatically in a thermo-dynamic engine, doing external work, and no heat is transferred from or into the air during the operation, then according to the formula of relations between pressures and temperatures

the final temperature of the air after expansion

$$t = t_1 \left(\frac{p}{p_1} \right)^{0.291}$$

in which t_1 and p_1 are the absolute temperature and pressure of the air before expansion, and t and p the absolute temperature and pressure of the air after expansion, the exponent

$$0.291 = \frac{1.41 - 1}{1.41} \quad 75$$

of which

$$1.41 = \frac{0.237}{0.168}$$

(the ratio of the specific heat of air at constant pressure to that at constant volume). In this case, also, the final temperature " t " is lowered and consequently the drop in temperature " d " is increased if the ratio of the higher to the lower pressure is increased, or if the temperature of the air before expansion is decreased. Now, assuming that the temperature of the air before expansion t_1 is 62 deg. F., then the drop in temperature for different ratios of expansion is:—

$$\begin{aligned} d &= 95 \text{ deg. F. for a ratio of 2,} \\ d &= 195 \text{ deg. F. for a ratio of 5,} \\ d &= 255 \text{ deg. F. for a ratio of 10,} \\ d &= 285 \text{ deg. F. for a ratio of 15.} \end{aligned}$$

In practice the drop in temperature will be very much less. A loss of from 15% to 50%, due to transmission of heat, inefficiency of motor, imperfect insulation, etc., may be expected.

In my system I prefer to operate the thermo-dynamic engine with ratios of from 5 to 15, although higher or lower ratios may be employed, but assuming that I operate the engine with a ratio of expansion of 10, and assuming also that the temperature of the air before expansion is 62° F., and the thermal losses = 50%, then the drop in temperature will equal about 127° F., as against a drop in temperature of about 4.5° F. due to free expansion under the same conditions. Besides the great gain in thermal advantages, about 50% of the work done in compressing the air may be recovered. The above calculations are only approximately correct.

In my present invention I make use of the counter-current, self-intensive principle, employing, however, as above stated, an adiabatic expansion device for the free expansion means, and my reasons for interposing a trap and separator between the coil, pipe or chamber carrying the compressed air and the thermo-dynamic engine, are these:—In counter-current, self-intensive apparatus operated by free expansion means, the small quantity of liquid air, if any, which may accumulate above the expansion valve, if free from frozen carbon dioxid, would not seriously interfere with the proper operation

of such means, but since the thermal efficiency of an adiabatic expansion device is so much greater than that of free expansion means, a considerable quantity of air will assume the liquid state in the pipe or coil above the adiabatic expansion device, and this liquid, if not removed, would seriously interfere with the proper operation of the adiabatic expansion device, if it did not practically make it inoperative. It must be understood, however, that only part of the compressed air can assume and remain in the liquid state above the throttle valve of the expansion device for the reason that a considerable quantity of heat equal to the latent heat of evaporation of liquid air will be liberated the moment the change from the gaseous to the liquid state takes place.

To make the apparatus commercially operative the liquid air and frozen carbon dioxide must be separated and removed from the coil so as to operate the adiabatic expansion device by compressed gaseous air only. For this purpose I employ a separator and trap, singly or in multiple.

I do not limit my invention to any special or particular construction of thermodynamic expansion device, separator or trap. Any suitable device or devices which will answer the purpose for which they are intended, may be employed; nor do I limit my invention to any mode of installation. The adiabatic expansion device, separator or trap, or either of them, may be placed within the liquefier proper, or they may be placed outside of the liquefier proper, properly insulated and connected to the counter-current coil or coils of the so-called liquefier.

Separator 40 consists of a vessel having the inlet connection 39 and the outlet connection for the gas 51 above the liquid outlet connection 41. In this separator 40 the liquid separates from the gaseous air by gravity. The liquid flows through pipe 41 into trap 42 which consists of an outer closed vessel 43 and an inner vessel or float 44 open at the top and movable vertically in the outer vessel, being guided therein by guide means 45 at the side, and a guide pin 45^a at the bottom working in a socket 45^b.

46 is a conical projection or valve plug on the bottom of vessel 44 which cooperates with a conical seat at the lower end of pipe 47 to form a valve 48 for controlling communication to said pipe.

The liquid air upon entering vessel 43 raises the inner vessel 44 and thereby closes the valve 48. When the level of the liquid reaches the top of vessel 44 it overflows into it, and upon reaching a certain level the vessel 44 sinks and thereby opens valve 48. The pressure maintained in the trap 42 is the same as that of the compressed air, and owing to this pressure the liquid is forced out

through pipes 47 and 49 into separator 50 in which a lower pressure is maintained.

49^a is a valve in pipe 49 controlling communication between trap 42 and separator 50, and 42^a is a connection and valve leading from trap 42.

The compressed air flows through pipe 51 to the adiabatic expansion device 53 which may consist of any suitable thermo-dynamic engine, expansion engine, motor or turbine. The throttle valve is shown at 52, and the stem 54 of this valve projects outside of the casing or the enclosure 55. In the adiabatic expansion device the compressed air may be allowed to expand from about 300 pounds to the square inch to a gage pressure of about 60 pounds to the square inch, and by doing so it performs external work and drops in temperature. The exhaust from the adiabatic expansion device, both liquid and gaseous air, flows through pipe 56 into separator 50 where they meet the liquid and gaseous air coming from trap 42 through pipe 49. It is understood that although liquid air alone can be discharged through the valve 48 of the trap 42, owing to the difference in pressures maintained in trap 42 and separator 50, so much of the liquid will evaporate upon passing valve 48 as is necessary to reduce its temperature to that of liquid air maintained under a pressure of 60 pounds to the square inch. The liquid air from separator 50 flows through pipe 57 into trap 58, similar in construction to trap 42.

57^a is a valve in pipe 57 controlling communication between the separator 50 and trap 58, and 50^a is a connection and valve leading from separator 50.

Part of the cold, unliquefied air passes from separator 50 through valve 59 and connection 69 into conduit 60 which incloses conduit 37, as will hereafter be described, and part of it is allowed to expand through valve 61 into receiver 63 from a pressure of about 60 pounds to the square inch to about atmospheric pressure. The air from separator 50, upon expansion through throttle-valve 61 drops in temperature. Part of it liquefies, and together with the unliquefied air it flows through connection 62 into receiver 63. The liquid air from trap 58 is discharged through connection 64 into receiver 63 in the manner heretofore described for trap 42. Owing to the difference in pressures maintained in trap 58 and receiver 63 so much of the liquid released from pressure of about 60 pounds to the square inch to about atmospheric pressure will evaporate as is necessary to reduce its temperature to that of the temperature of liquid air at atmospheric pressure; viz., about 312.6 deg. below zero F. The liquid air may be withdrawn from receiver 63 through valve 65^a and connection 65. The unliquefied cold air

115

120

125

from receiver 63 flows through connection 66 into conduit 67 which envelops or surrounds conduit 60. The cold air of the pressure of about 60 pounds to the square inch flows 5 through conduit or channel 60 in a direction opposite to that of the incoming compressed air, which is of a higher temperature and which flows through conduit or pipes 37, and in doing so it absorbs heat from it and gradually reduces its temperature. The cold air 10 in conduit 67 flows in the same direction as that in conduit 60 and serves as an insulator for the air within the inner channels or conduits 60 and 37 as well as a heat-absorbing medium. Pipe connections or passages 68 lead from the respective high pressure, intermediate pressure and low pressure chambers and channels 51, 50 and 63, and are connected to suitable pressure gages to enable 15 the attendant to ascertain the pressures in the respective chambers. The entire system of piping of the liquefier is inclosed or embedded in suitable heat-insulating material, indicated at A, which in turn is inclosed in 20 casing 72. From the return conduits 60 and 67 of the liquefier the expanded air is led by pipes 70 and 71 through the external conduits of the counter-current apparatus above referred to. The pipe 71 from the low-pressure 25 conduit 67 of the liquefier leads to one end of the external conduit 21 of section 18 of the counter-current apparatus, connection being made from the other end of such conduit 21, through the pipe 73 and valve 74, 30 to the intake-pipe 75 of the compressor. The pipe 70 leads from the intermediate-pressure conduit 60 of the liquefier to one end of the external-pressure conduit 27 of section 19 of the counter-current apparatus. 35 The third section 20 of the counter-current apparatus is desirably cooled by the utilization of the same current of air that cools section 19. This air at the intermediate pressure, in passing through section 19, 40 has absorbed so much heat that to enable it to be used in further cooling it is necessary to reduce its temperature by allowing it to expand. Such expansion may be performed in any suitable apparatus, but I prefer to 45 provide for this purpose a thermo-dynamic engine or expansion device 80 wherein the air is caused to perform external work in the act of expansion. The outer casing 27 of section 19 is connected to the thermodynamic 50 engine by pipe 76, valve 105, heater 100, pipe 79, valve 106 and pipe 81. Assuming that the return current of air of the intermediate pressure in flowing through the return conduit 60 of the liquefier and return 55 conduit 27 of section 19 and all connections to the thermodynamic engine 80, absorbed enough heat to reach a temperature of about 62° F., then according to the formula of relations between pressures and temperatures 60 due to adiabatic expansion, as heretofore

cited, the drop in temperature for a ratio of expansion of 5 will equal about 195 degrees F., (in practice about 15% less), giving a final temperature of about 104 degrees below zero F. Besides this great drop in temperature, the effect of which will be utilized for cooling section 20, about 50% of the work done in the compressor while compressing this amount of air to a gage pressure of 60 pounds to the square inch, may be recovered. 75

The exhaust side of the thermodynamic engine 80 is connected by pipe 82 to a trap 83 provided with a draw-off cock 84 which in turn is connected by pipe 85 to one end of the external conduit 31 of section 20, the other 80 end of said external conduit 31 being connected through pipe 92 and valve 93 to the pipe 71 leading to the outer conduit of section 18, from which connection is made as above described to the low-pressure compressor cylinder. Valves 94, 95, are provided in pipe 71, one on each side of the junction with pipe 92. The air that passes from the expansion engine to the final section 20 of the counter-current apparatus may be assumed to have a temperature of about -104 degrees F., and the compressed air that passes from section 20 will, therefore, enter the liquefier at a somewhat higher temperature, say from -50 degrees F., to -75 degrees F., so that it will not be possible for it to contain aqueous vapor or oil to an extent sufficient to interfere with the operation, it being understood that the temperature of the outgoing compressed air from section 20 will 95 vary with the temperature of the incoming air and the proportion of the air in the outer conduit to that in the inner one. From two-thirds to four-fifths of the total amount of air 100 expanded in motor 53 passes thus through the return conduit 31 of section 20 and leaves the same at from 0 degrees F. to -20 degrees F., and it is then led through pipe 92 and valve 93 so as to join the balance of the air passing 105 through pipe 71 which may be assumed to have a temperature of about -80 degrees F. The combined quantity of air will then pass 110 to section 18 so that all the air delivered by the compressor, except that which has been liquefied, or in any other way wasted by blowing out, etc., is utilized in cooling this section. The temperatures above given are only approximate.

77 indicates a valve controlling a direct connection from pipe 76 to the high pressure compressor cylinder 4. 120

88 indicates a valve which controls communication from the intake pipe 75 to the outer air; this valve is a self-regulating check valve set to a certain pressure so as to admit 125 only the required amount of atmospheric air.

97, 98 and 99 designate draw-off valves or cocks communicating with pipes or conduits 86, 76 and 73, to enable the gaseous contents thereof to be withdrawn when desired. 130

Taps or cocks 104 are provided at the lowest points of the return conduits 21, 27 and 31 to draw off condensed substances which may accumulate. It will be understood 5 that foreign substances will not deposit in these pipes except under unusual conditions.

In practice, if operating with atmospheric air, a gas rich in nitrogen may be drawn from cocks or valves 97 or 98, or a gas rich in 10 oxygen may be drawn from cock 99 as hereinafter explained. Connections may be made with gasometers or other means for storing the gases for future use.

100 designates a heater or warmer that 15 may be interposed in the connection 79 from pipe 76 to pipe 81 whereby the air that is delivered at intermediate pressure to the motor or expansion engine 80 may be warmed before expansion so as to increase 20 the efficiency of the engine, or not to permit too low a temperature therein. I prefer to keep the air entering the engine 80 at a temperature of about 60 degrees F. although a lower or higher temperature may be maintained. 25 This warmer or heater may absorb the heat from the surrounding atmosphere, or, as shown, may be provided with an external casing 101 through which water or other medium is circulated by pipe connections 30 102, and the outlet of said casing may be connected through valve 110 with the water supply pipes 8 of the compressor, so as to utilize the same water for the compressor. A water supply pipe 107 and valves 108, 109 35 are provided for enabling the circulating water to be supplied to the compressor when the device 100 is omitted or not in use.

115 are tubes inclosing the shaft 116 of the motor 53, so as to prevent the revolving shaft 40 from coming in contact with the insulation. The bearings 117 of the motor which require oiling are outside of the casing 55.

The mechanical energy developed by the 45 motors or expansion engines 53 and 80 may be utilized in any suitable manner.

It will be understood that the liquefier and the entire regenerative apparatus, including the cooler sections 18, 19 and 20, and their traps, are properly protected from absorption 50 of heat from the outer air by thorough insulation thereof in well known manner. The expansion engine 80 is also insulated. To avoid confusion, the insulating materials *a* and *A* are mostly omitted from the 55 views.

To construct and successfully and 60 economically operate a plant for the manufacture of liquid air by the adiabatic expansion, accumulative, self-extensive or regenerative process, or for the manufacture of commercial gaseous oxygen and nitrogen which involve, first, the liquefaction of air and then 65 its separation into commercial oxygen and nitrogen by fractional distillation; and to keep the apparatus in continuous operation,

it is essential—First:—That means should be provided for the total removal of the heat due to the last compression and before the compressed air enters the liquefier. Second: That the compressed air before entering the liquefier should, as nearly as practicable, be free from the aqueous vapor or moisture contained therein and from the oil used in lubricating the cylinders of the compressor. Third: As much as possible of the carbon 70 dioxide, liquid or solid, should be removed from the compressed air before it reaches the liquefier, and practically none should be permitted to enter the adiabatic expansion devices. Fourth: A trap or traps should be 75 located at any point or points in the system where there is an upward bend of a junction of descending and ascending pipes. Fifth: Means should be provided for the removal of that part of the air which assumed the 80 liquid state before reaching the expansion device. Sixth: All expansion and counter current means should be thoroughly insulated from the heat of the outer atmosphere, and the same is true of the pipes and 85 traps carrying air at a temperature below 90 degrees F., except at the outlets.

The operation of the apparatus for the production of liquid air and commercial gaseous oxygen and nitrogen may be described as follows: Valve 88, admitting atmospheric air to the compressor will, in general, be open. In starting, valve 35 leading to the liquefier, will be closed,—valves 91 and 106 admitting compressed air directly to the motor 80 from the last cooler section 20, will be opened. Valve 111 may be opened and valves 93, 74, 105 and 77 closed so as to deliver the exhaust from this motor through the external conduit of section 20 directly back to the compressor. Under these conditions, only section 100 20 will be used in cooling. Atmospheric air will be drawn in through valve 88 and will be subject to successive compressions in the cylinders 3 and 4 of the 105 compressor to a pressure of about 300 lbs. to the square inch, the heat due to compression being absorbed by the water jackets and inter-cooler up to the last stage, from which the compressed air is discharged in heated 110 condition, only so much of the heat of the last compression having been absorbed as can be taken up by the water jacket of, and radiated and conducted from the high pressure cylinder. From this cylinder the compressed air passes to the trap 10 where it 115 parts with the oil carried over in a liquid form, and owing to the relatively lower temperature of the trap the compressed air also parts with part of its moisture, and then 120 passes through the preliminary cooler 12, wherein it interchanges temperature with the air drawn through pipe 16 by the cylinder 2 of the internal combustion engine and is cooled to about the temperature of the at- 125 130

mosphere. The compressed air then flows through pipe 17 into trap 24 and through conduit 22 of section 18. The moisture and vaporizing oil which have condensed during the process of cooling in interchanger 12 will deposit in traps 10 and 24, for it is well known that when air containing aqueous vapor is cooled, the temperature of the vapor is lowered with the result that its density is increased until the vapor reaches a maximum density for the corresponding temperature. If the temperature is still lowered, part of the vapor will condense, and if the cooling is gradual and the flow of air is slow and takes place in vertical or inclined pipes provided with traps, the condensed vapor will flow down into the traps from which it may be removed. From conduit 22 the compressed air flows into and through conduit 26 of section 19, then through conduit 30 of section 20 and through connection 90 and valves 91 and 106 to the intake side of the expansion engine 80. In passing through this engine the air is expanded adiabatically or nearly so, and is reduced in pressure and in temperature. The cold, expanded air passes through pipe 82, trap 83, and pipe 85 to the external conduit 31 of cooler section 20, then by pipe 86 and valve 111 back to the compressor. It will be understood that the compressor will not, under these conditions, be working to a pressure beyond the capacity of the expansion engine.

The operation described will result in a regenerative or accumulative cooling of section 20 to a temperature sufficiently low to deposit the greater part of the vaporized oil and aqueous vapor of the compressed air, so that the compressed air may then be admitted to the liquefier without danger of clogging. In order, however, to similarly cool the section 18 in addition to section 20 and thereby further protect the liquefier, the valves 111, 105, and 77 may be closed, and valves 93, 95 and 74 opened. The cold exhaust from the expansion engine 80 will then flow first through conduit 31 of section 20, as above explained, and then through pipes 92, 71 and external conduit 21 of section 18, and through pipes 73 and 75 to the intake of the low pressure cylinder 3 of the compressor. The compressed air having been cooled in counter-current sections 18 and 20, as above described, to a sufficiently low temperature, valves 35, 94, 93, 95, 74 and 105 are opened and the valves 91, 111 and 77 closed. Valves or cocks 97, 98 and 99 are generally closed. The compressed air now passes through valve 35 into the internal conduit or coil 37 of the liquefier, thence through header 38 and connection 39 into separator 40, and through pipe 51 into motor 53, where it expands adiabatically or nearly so, from a pressure of about 300 lbs. to the square inch to a pressure of about 60 lbs. to the square

inch. In starting the liquefier, valves 49^a and 57^a are kept closed until liquid begins to accumulate in separators 40 and 50. The presence of liquid can be detected by opening valves or cocks 42^a and 50^a. Upon the appearance of liquid, valves 49^a and 57^a are opened so as to establish direct communication between separator 40, trap 42, separator 50, trap 58 and receiver 63 for the automatic discharge of liquid. The air, during the process of expansion, as heretofore explained, drops in temperature. The cold exhaust from motor 53 flows through connection 56 into separator 50. From two-thirds to four-fifths of this cold air of the intermediate pressure is caused to flow by connection 69 through conduit 60 which surrounds conduit or pipe 37 and in a direction opposite to that of the flow of the compressed air within said conduit 37. An interchange of temperature takes place: the cold air of the intermediate pressure absorbs heat from the compressed air making the cooling effect of said compressed air accumulative to such a degree that part of it assumes the liquid state in the lower part of conduit 37. The flow of the air from separator 50 into conduit 60 is regulated by valve 59. The pressure maintained in conduit 37 is about 300 lbs. to the square inch and that in separator 50 about 60 lbs. to the square inch. Now, since the temperature of liquid air under pressure of 60 lbs. to the square inch is about 280° below zero F. and since the temperature required for liquefying air under a pressure of 300 lbs. to the square inch is about 228° below zero F., and as the vapor used for cooling the air in conduit 37 is taken from separator 50, the temperature of which vapor is also about 280° below zero F., it follows that the temperature of the cooling medium in conduit 60 is low enough to liquefy part of the air in the lower part of conduit 37. The liquid air from separator 40 flows through connection 41 into trap 42, and from the latter through connection 49 into separator 50, in the manner heretofore described.

As above stated, from two-thirds to four-fifths of the air of the intermediate pressure in separator 50 will be allowed to pass through connection 69 into the intermediate conduit 60; the balance will be allowed to expand freely through valve 61. This air, of a temperature already very low, will upon expansion from a pressure of 60 pounds to the square inch to about atmospheric pressure, drop in temperature sufficiently to convert part of it into liquid which will, together with the unliquefied air, flow through connection 62 into receiver 63. The liquid air from separator 50 will flow through connection 57, trap 58, and connection 64; also into receiver 63 and may be withdrawn from said receiver through valve 65^a and connection 65. The unliquefied air will pass 130

through connection 66 into conduit 67 which surrounds conduit 60. As the air in conduit 67 flows in the same direction as that in conduit 60 it will serve as an insulating medium 5 as well as a cooling medium. The attendant guiding himself by the pressure gages, manipulates valves 52, 61 and 59 so as to maintain the proper relative pressures in the respective conduits, separators, etc. The 10 pressure in pipe 71 leading from the liquefier to valve 94 is maintained slightly higher than in pipe 92 leading from cooler 20. From the liquefier the air at the intermediate pressure of about 60 pounds to the square inch, 15 passes through pipe 70 to external-conduit 27 of section 19, wherein it absorbs heat from the compressed air, and therefore leaves said section comparatively warm. From conduit 27 the air flows through pipes 20 76, 79, to the motor or expansion engine 80, where it is expanded to about atmospheric pressure and considerably reduced in temperature. The cold exhaust from this engine passes by pipe 85 to cool the section 20, 25 as above explained. From conduit 31 of section 20 the cold air passes through the pipes 92 and 71 into the outer casing 21 of section 18 and thence through pipes 73 and 75 to the low pressure cylinder 3 of the compressor; or it may be allowed to escape from valve 99. In case all of the air supplied at intermediate pressure is not required for operating the expansion engine 80, then valve 77 may be opened to cause any desired 30 proportion of such air to pass directly to the intake end of the high-pressure cylinder 4.

The low-pressure cold air from receiver 63 which may comprise from one-third to one-fifth of the total quantity of air passing into 40 the liquefier, and is of a lower temperature than the air or liquid in separator 50, passes through connection 66 into conduit 67 which surrounds conduit 60, forming a cold envelop for said conduit for its whole length and 45 passing out through pipe 71 and valve 94, where it mixes with the air coming through pipe 92 from section 20, and, together they pass through valve 95 to the outer casing 21 of the first section 18 of the countercurrent 50 apparatus. Upon leaving this section it passes by pipe 73 and valve 74 to the intake of the low-pressure cylinder 3.

In utilizing this system and apparatus for the separation of atmospheric air into commercial oxygen and nitrogen, the condensed product is allowed to accumulate in receivers 50 and 63. The product of evaporation from receiver 50 will be a gas rich in nitrogen; the remaining liquid will be rich in oxygen. 55 This liquid rich in oxygen will flow, as before described, through trap 58 into receiver 63 in which it will be allowed to evaporate. The 60 evaporated gases from receivers 50 and 63 will flow through connections and conduits

already described and may be withdrawn 65 through valves or cocks 97 and 99. It may be observed that in this instance trap 58 will prevent the passage of gas, rich in nitrogen, from receiver 50 into receiver 63; valve 61 may be closed. When making commercial 70 oxygen and nitrogen in this manner, valves 111 and 93 are closed so as to direct the nitrogen from conduit 31 of section 20 to valve 97, and prevent it from mixing with the oxygen flowing through pipe 71, while valve 74 75 is closed to cause the oxygen to pass out at valve 99. Valve 77 is also closed to prevent nitrogen from passing into compressor-cylinder 4. The valves can be so manipulated as to draw either oxygen or nitrogen. Suitable 80 connections and storage means will, of course, be provided to receive the commercial oxygen and nitrogen.

To facilitate or to increase the evaporation in receiver or separator 50, said receiver may 85 be filled with glass beads or glass wool or any other suitable material, shown at 179 in Fig. 3, so as to enlarge the surface of contact, or a coil 180, as shown in Fig. 4, may be introduced in said separator communicating with 90 connection 51 so as to permit part of the compressed air flowing through pipe or connection 51 to pass through said coil to impart heat to the liquid air within receiver 50. 181 is a valve to regulate the amount of air to 95 be passed through coil 180. The contents from said coil 180 may discharge directly into receiver 50.

It will be noted that there is a connection around the thermodynamic engine; that is 100 to say, between the high and low pressure sides of said engine, said connection leading through pipe 41, trap device 42 and its valve 48, and pipe 49 to the separator 50, on the low-pressure side of the engine, this connection being closed by valve 49^a until liquid begins to accumulate in trap 42. When enough liquid has accumulated in trap 42 to raise the inner vessel 44 sufficiently to close valve 48, then valve 49^a is opened and the 110 trap begins to automatically discharge the liquid from separator 40 into separator 50. This is an important feature, as it prevents the passage of liquid through the engine. The main difficulty in the use of a thermodynamic engine in this connection was the 115 interference with its operation due to presence of liquefied product therein, and the above-described automatically-opening valve enabled me to overcome this difficulty. 120

The above-described system and apparatus for the liquefaction of air or other gases is best adapted for moderate size plants where efficiency is a primary factor and cost of installation a secondary; but for small plants, 125 or where it is desirable or convenient to operate the plant with comparatively low pressures from 100 to 250 lbs. to the square inch,

the modified system and apparatus illustrated in Figs. 5 and 6 and hereinafter described, may be found most desirable.

In Fig. 5, 1 represents the compressor. 5 200 is the power cylinder, preferably an internal combustion engine; 201 and 202 are the respective low and high pressure air or gas compressing cylinders. 203 is the inter-cooler, and 204 and 205 represent the connections for the circulating water or other heat-absorbing medium. Air is admitted to the compressor through self-regulating valve 188 and connection 175, and is compressed successively in cylinders 201 and 202 10 to about 150 lbs. to the square inch. The compressed air from cylinder 202 flows through connection 206 and trap 207 into a modified form of heat-interchanger 182 which consists of an outer casing 183 with 15 longitudinal passages 184 for the conveyance of the compressed air, and a chamber 185 surrounding said passages for the conveyance of the cooling medium, which in this case also is the air required for forming the explosive mixture for the internal-combustion engine 200. The air which is admitted through connections 209 flows around passages 184 and enters cylinder 200 through connection 210. 208 is a draw-off cock leading 20 from trap 207. The compressed air from interchanger 182 flows through connection 211 into trap 212; thence through the inner conduit 122 of temperature-interchanger 118 and through connection 213 and inner conduit 130 of temperature-interchanger 120. From conduit 130 the compressed air flows through valve 135 into and through conduit 137 of the so-called liquefier. The lower end of conduit 137 is connected to 25 separator 140 from which connection 141 leads to a trap 142, and connection 151 and throttle-valve 152 to a thermo-dynamic expansion device 153. A connection 214 and valve or cock 215 lead from separator 140 to the outside of the casing which incloses the separator. The trap 142 is connected to receiver 150 by pipe 149, and the exhaust side of the engine 153 is also connected to receiver 150 by connection 216. 217 is a valve controlling 30 communication between separator 140 and trap 142. The receiver 150 is connected by pipe 169 to the lower end of conduit 160 which envelops or incloses conduit 137. The upper end of said conduit connects by pipe or channel 171 to one end of the outside casing or conduit 121 of temperature-interchanger 118. The other end is connected by conduit 173, valve 174 and conduit 175 to the intake side of the low pressure cylinder 201. The gages 168 indicate the pressures in separator 140 and receiver 150. 125 and 126 are connections for the circulation of a refrigerating medium through the outer casing 131 which envelops 35 conduit 130 of section 120. 124 and 128 are traps with outlet cocks 133 located at the lowermost points of conduits 122 and 130. The whole system requiring protection from heat is properly insulated in the well-known manner.

The operation is as follows:—Before starting the compressor 1, the inner and outer conduits 130 and 131 of section 120 are cooled down to a temperature lower than 20° F. by the circulation of some refrigerating medium such as expanded ammonia, carbon dioxide, or cooled brine. When this is done then the compressor is started and valve 217 is closed. The compressed air from cylinder 202 flows through conduit 206 into trap 207 where it deposits the oil used for lubricating the compressor cylinders and also part of the moisture. This oil and condensed moisture can be removed from trap 207 through valve or cock 208. From trap 207 the compressed air flows through the passages 184 of cooler 182 where it interchanges temperature with the air drawn in by cylinder 200 of the internal-combustion engine, as heretofore described. The compressed air leaves the cooler 182 at 40 about the temperature of the atmosphere and flows through the inner conduits 122 and 130 of temperature-interchangers 118 and 120, then through conduit 137 of the counter-current coil of the so-called liquefier in the manner heretofore described. From conduit 137 the compressed air flows through separator 140, connection 151 and throttle-valve 152 into the thermodynamic engine 153, where it is made to expand adiabatically, or nearly so, to about atmospheric pressure. In the process of expansion the air performs external work and drops in temperature. The cold expanded air from engine 153 is discharged into receiver 150, and 45 it flows through connection 169 into conduit 160 which envelops or surrounds conduit 137. The cold expanded air flows through conduit 169 in a direction opposite to that of the flow of the compressed air in conduit 137, and by doing so it absorbs heat from the latter and makes the cooling effect of the compressed air accumulative to such a degree that upon expansion through motor 153 part of it liquefies. When the cold vapor of 50 the temperature of liquid air begins to flow through connection 169 into conduit 160, it reduces the temperature of the compressed air in the lower part of conduit 137 to such a degree that part of it assumes the liquid state. The presence of liquid in receiver 140 may be detected by opening valve 215; valve 217 is then opened and the liquid from separator 140 is allowed to flow through connection 141 into trap 142; thence through connection 149 into receiver 150 in the manner described for trap 42 of Fig. 1. The liquid air may be withdrawn from receiver 150 through valve 164 and connection 165, and the unliquefied air, together with the prod-

uct of evaporation of the liquid in receiver 150, is made to flow in the manner heretofore described through connection 169 and conduit 160. It may be observed that since the compressed air enters into conduit 137 at a temperature lower than 20° F., the expanded air leaving conduit 160 must be of a temperature somewhat lower than that of the compressed air, and therefore this expanded cold air, which is still of a low temperature, can be used for cooling the compressed air flowing through the inner conduit 122 of section 118. Accordingly, the expanded cold air upon leaving conduit 160 flows through connection 171 and the outer conduit 121 of section 118, and in a direction opposite to that of the compressed air, and by doing so it absorbs heat from the latter. The expanded air on leaving the outer conduit 121 of section 118 may be discharged into the atmosphere through valve 199, or it may be allowed to flow through connection 173, valve 174 and connection 175, to the intake end of the low-pressure cylinder 201 of the compressor.

It is to be understood that although the circulating refrigerant is shown in Fig. 5 as cooling the compressed air in section 120, and the cold expanded air from the liquefier as cooling the compressed air flowing through section 118, the system may be reversed; the refrigerating medium may be used for cooling section 118, and the cold expanded air from the liquefier may be made to cool section 120.

In large plants it may be desirable and profitable to perform both the above described expansions adiabatically, and the expansion means, separators, traps, etc., placed outside of the liquefier proper, properly insulated, as shown in Fig. 7. The lower part of conduit 370 is connected by header 380 and pipe 390 to separator 400, the upper part of which is connected by pipe 510 and throttle-valve 520 to motor 530. 420 is a trap, and connection 410 and valve 490^a control communication between separator 400 and trap 420. 420^a is a pipe and valve leading from bottom of separator 400. 490 is a connection leading from trap 420 to separator 500, and 560 is a connection leading from the exhaust side of motor 530, also to separator 500. From separator 500, pipe 690 and valve 590 control communication to conduit 600; pipe 620 and valve 610 control communication to motor 800, and connection 570 leads to trap 580. Pipe 640 and valve 570^a control communication between trap 580 and receiver 630, and 700 is a connection between the exhaust end of motor 800 and receiver 630. Pipe 660 leads from receiver 630 to the outer conduit 670. 650^a is a valve, and 650 is a pipe leading from receiver 630 for the discharge of liquid. 680 are pressure gages connecting with separators 400 and

500, respectively, and receivers 630. The operation is the same as described for Fig. 1, except that the second expansion is also performed by thermodynamic means, and the liquid and gas from the thermodynamic means 800 flow into receiver 630 from which the liquid may be withdrawn through valve and connection 650^a and 650, and the gas returned by connection 660 to the outer conduit 670, as before described.

What I claim is:—

1. In a gas liquefying system, means for compressing and cooling gas, a liquefied gas separator a trap having a connection therewith and adapted to separate and automatically remove the liquefied gas from the cooled compressed gas, an expansion device connected to receive gas from said separator and operating to partially liquefy the gas in the expansion thereof, a receiver connected to the low pressure side of the expansion device adapted to separate the liquefied from the unliquefied gas after expansion.

2. In a gas liquefying system, means for compressing and cooling gas, a liquefied gas separator a trap having a connection therewith and adapted to separate and automatically remove the liquefied gas from the cooled compressed gas, an expansion device connected to receive gas from said separator and operating to partially liquefy the gas in the expansion thereof, a receiver connected to the low pressure side of the expansion device adapted to separate the liquefied from the unliquefied gas and means for withdrawing the liquefied gas from said receiver.

3. In a gas liquefying system, means for compressing and cooling gas, a separator adapted to separate liquefied gas from the cooled compressed gas, a trap connected to the separator and adapted to remove the liquefied air, an expansion device connected to receive gas from the separator and operating to partially liquefy the gas in the expansion thereof, a receiver connected to the low pressure side of the expansion device and adapted to separate the liquefied from the unliquefied gas after expansion.

4. In a gas liquefying system, means for compressing and cooling gas, a separator adapted to separate liquefied gas from the cooled compressed gas, a trap connected to the separator and adapted to remove the liquefied gas, an expansion device connected to receive gas from the separator and operating to partially liquefy the gas in the expansion thereof, a receiver connected to the low pressure side of the expansion device to separate the liquefied from the unliquefied gas, and means for withdrawing the liquefied gas from said receiver.

5. In a gas liquefying system, means for compressing and cooling gas, a liquefied gas separator a trap having a connection therewith and adapted to separate and automat-

- ically remove the liquefied gas from the cooled compressed gas, a thermodynamic engine connected to receive gas from said separator and operating to partially liquefy the 5 gas in the expansion thereof, a receiver connected to the low pressure side of the thermodynamic engine adapted to separate the liquefied from the unliquefied gas after expansion.
- 10 6. In a gas liquefying system, means for compressing and cooling gas, a liquefied gas separator a trap having a connection therewith and adapted to separate and automatically remove the liquefied gas from the 15 cooled compressed gas, a thermodynamic engine connected to receive gas from said separator and operating to partially liquefy the gas in the expansion thereof in said engine, a receiver connected to the low pressure side of the engine adapted to separate the liquefied from the unliquefied gas and means for withdrawing the liquefied gas from said receiver.
- 20 7. In a gas liquefying system, means for compressing and cooling gas, a separator adapted to separate liquefied gas from the cooled compressed gas, a trap connected to the separator and adapted to remove the liquefied gas, a thermodynamic engine connected to receive gas from the separator and 25 operating to partially liquefy the gas in the expansion thereof in said engine, a receiver connected to the low pressure side of the engine and adapted to separate the liquefied from the unliquefied gas after expansion.
- 30 8. In a gas liquefying system, means for compressing and cooling gas, a separator adapted to separate liquefied gas from the cooled compressed gas, a trap connected to the separator and adapted to remove the 35 liquefied gas, a thermodynamic engine connected to receive the gas from the separator and operating to partially liquefy the gas in the expansion thereof in said engine, a receiver connected to the low pressure side of the engine adapted to separate the liquefied from the unliquefied gas and means for withdrawing the liquefied gas from said receiver.
- 40 9. In a gas liquefying system, means for compressing and cooling gas, a separator adapted to separate liquefied gas from the cooled compressed gas, a thermodynamic engine connected to receive gas from the separator and operating to partially liquefy the gas in the expansion thereof in said engine, a receiver connected to the low pressure side of the engine adapted to separate the liquefied from the unliquefied gas, and means for withdrawing the liquefied gas from said receiver.
- 45 10. In a gas liquefying system, means for compressing and cooling gas, a separator adapted to separate liquefied gas from the cooled compressed gas, a thermodynamic engine connected to receive gas from the separator and adapted to partially liquefy the gas in the expansion thereof in said engine, a throttle valve located on the high pressure side of the engine, and a receiver connected to receive the exhaust from the engine and adapted to separate the liquefied from the unliquefied gas after expansion.
- 50 11. In a gas liquefying system, means for compressing and cooling gas, a liquefied gas separator, a trap having a connection therewith and adapted to separate and automatically remove the liquefied gas from the cooled compressed gas, a thermodynamic engine connected to receive gas from said separator and adapted to partially liquefy the 55 gas in the expansion thereof in said engine, a throttle valve located on the high pressure side of the engine, a receiver connected to receive the exhaust from the engine and adapted to separate the liquefied from the unliquefied gas after expansion.
- 60 12. In a gas liquefying system, means for compressing and cooling gas, a liquefied gas separator, a trap having a connection therewith and adapted to separate and automatically remove the liquefied gas from the cooled compressed gas, a thermodynamic engine connected to receive the gas from said separator and adapted to partially liquefy the 65 gas in its passage through the engine, a throttle valve located on the high pressure side of the engine, a receiver connected to receive the exhaust from the engine and adapted to separate the liquefied from the unliquefied gas after expansion.
- 70 13. In a gas liquefying system, means for compressing and cooling gas, a separator adapted to separate the liquefied gas from the cooled compressed gas, a trap connected to the separator and adapted to remove the liquefied gas, a thermodynamic engine connected to receive gas from the separator and adapted to partially liquefy the gas in its passage through the engine, a throttle valve located on the high pressure side of the engine, a receiver connected to the outlet of the engine, and means for withdrawing liquid from said receiver.
- 75 14. In a gas liquefying system, means for compressing and cooling gas, counter-current temperature interchanging means, a separator connected to the high pressure channel of the counter current means and adapted to separate the liquefied from the unliquefied gas, a thermodynamic engine connected to receive gas from the separator, a throttle valve located on the high pressure side of the engine, a receiver connected to the low pressure side of the engine, and means for directing the flow of the unliquefied gas from the receiver through the low pressure channel of the counter-current means.
- 80 15. In a gas liquefying system, means for compressing and cooling gas, counter-current temperature interchanging means, a separator connected to the high pressure channel of

the counter current means and adapted to separate the liquefied from the unliquefied gas, a thermodynamic engine connected to receive gas from the separator, a throttle valve located on the high pressure side of the engine, a receiver connected to the low pressure side of the engine, and means for directing the flow of the unliquefied gas from the receiver through the low pressure channel of the counter-current means, and means for withdrawing the liquefied gas from said receiver.

16. In a gas liquefying system, means for compressing and cooling gas, a separator adapted to separate the liquefied gas from the cooled compressed gas, a thermodynamic engine connected to receive gas from the separator, a throttle valve located on the high pressure side of the engine, a receiver connected to the low pressure side of the engine, and means for withdrawing the liquefied gas from the receiver.

17. A liquefying system for gases comprising expansion cooling means, self-intensive counter current conduits connected to said expansion means, a separator located between the high pressure conduit of the counter current means and the expansion means, a receiver connected to the low pressure side of the expansion means for receiving the exhaust therefrom, and a valved connection around the expansion means connecting the separator on the high pressure side of the expansion means with the receiver on the low pressure side of the expansion means.

18. A liquefying system for gases, comprising expansion cooling means, a receiver having a connection therewith, self-intensive counter current conduits connected to said expansion means, a separator located between the high pressure conduit of the counter-current means and the expansion means, and a connection around the expansion means controlled by a valve operating automatically to open and allow passage of fluid from the separator to the receiver.

19. In a gas liquefying system, the combination of means for cooling and compressing said gases, and a gas liquefier comprising high and low pressure counter-current conduits for partially liquefying said gases, a liquefied gas separator receiving from said high pressure conduit the liquefied and unliquefied portions of said gases, a thermo-dynamic engine having a valved connection with said separator, a receiver connected with the low pressure side of said engine and a conduit controlled by a hand valve and an automatic liquid trap and connecting the high pressure side of said engine with said receiver.

20. In a gas liquefying system, a liquefied gas separator, a thermo-dynamic engine having a valved connection with the gas inlet of said separator, and a valve controlled conduit connection around said engine between the high and low pressure sides of the same.

21. In a gas liquefying system, means for compressing and cooling gas, counter-current temperature interchanging means, a separator connected to the high pressure channel of the counter-current means and adapted to separate the liquefied from the unliquefied gas, an expansion device connected to receive gas from the separator, a receiver connected to the low pressure side of the expansion device and adapted to separate the liquefied from the unliquefied gas, means for discharging the liquefied gas from the separator connected to the high pressure side of the expansion device into the receiver connected to the low pressure side of the expansion device, means for directing the flow of unliquefied gas from the receiver through the low pressure channel of the counter-current means, and means for withdrawing the liquid from the last named receiver.

22. In a gas liquefying system, means for compressing and cooling gas, counter-current temperature interchanging means, a separator connected to the high pressure channel of the counter current means and adapted to separate the liquefied from the unliquefied gas, a thermodynamic engine connected to receive gas from the separator, a receiver connected to the low pressure side of the thermodynamic engine and adapted to separate the liquefied from the unliquefied gas, means for discharging the liquefied gas from the separator connected to the high pressure side of the thermodynamic engine into the receiver connected to the low pressure side of the expansion device, means for directing the flow of unliquefied gas from the receiver through the low pressure channel of the counter-current means, and means for withdrawing the liquid from the last named receiver.

23. In a gas liquefying system, means for compressing and cooling gas, counter-current temperature interchanging means, a separator connected to the high pressure channel of the counter current means and adapted to separate the liquefied from the unliquefied gas, a thermodynamic engine connected to receive gas from the separator, a valve located on the high pressure side of the engine, a receiver connected to the low pressure side of the thermodynamic engine and adapted to separate the liquefied from the unliquefied gas, means for discharging the liquefied gas from the separator connected to the high pressure side of the thermodynamic engine into the receiver connected to the low pressure side of the thermodynamic engine, means for directing the flow of unliquefied gas from the receiver through the low pressure channel of the counter-current means, and means for withdrawing the liquid from the last named receiver.

24. In a gas liquefying system, means for compressing and cooling gas, counter current

temperature interchanging means comprising high, intermediate and low pressure channels, a thermodynamic engine propelled by the compressed gas flowing through the high pressure channel of the counter current means adapted to expand the gas to an intermediate pressure, a separator adapted to receive the partially liquefied gas from the engine, an expansion device adapted to expand 5 part of the gas from said separator from an intermediate to a low pressure, a receiver adapted to receive the partially liquefied gas from the expansion device, means for connecting the intermediate pressure separator 10 from the intermediate pressure channel of the counter current means, means for connecting the low pressure receiver with the low pressure channel of the counter current means, and means for connecting the intermediate pressure separator with the low pressure receiver. 15

20 25 25. In a gas liquefying system, means for compressing and cooling gas, counter current temperature interchanging means comprising high, intermediate and low pressure channels, a thermodynamic engine propelled by the compressed gas flowing through the high pressure channel of the counter current means, adapted to expand the gas to an intermediate pressure, a separator adapted to receive the partially liquefied gas from the engine, an expansion device adapted to expand part of said gas from the separator from an intermediate to a low pressure, a receiver 30 35 40 45 adapted to receive the partially liquefied gas from the expansion device, means for connecting the intermediate pressure separator with the intermediate pressure channel of the counter current, means for connecting the low pressure receiver with the low pressure channel of the counter current means, means for connecting the intermediate pressure separator with the low pressure receiver, and means for withdrawing liquid from the low pressure receiver.

50 55 60 65 26. In a gas liquefying system, means for compressing and cooling gas, high and low pressure counter current conduits, said high pressure conduit receiving the compressed cooled gas at high pressure, a separator connected to the said high pressure conduit to separate liquefied gas therefrom, a thermodynamic engine connected to receive and partially liquefy the gas from the separator, a separator connected to the outlet of the engine to separate liquid therefrom, a free expansion device connected to the last-named separator to receive and expand the gas therefrom, a receiver connected to receive the partially liquefied gas from the free expansion device, means for withdrawing liquid from said receiver and a connection from the low pressure side of the engine to the low pressure conduit of the counter current apparatus.

70 75 80 85 27. In a gas liquefying system, means for compressing and cooling gas, high and low pressure counter current conduits, said high pressure conduits receiving the compressed cooled gas at high pressure, a separator connected to the said high pressure conduit to separate liquefied gas therefrom, a thermodynamic engine connected to receive and partially liquefy the gas from the separator, a separator connected to the outlet of the engine to separate liquid therefrom, a free expansion device connected to the last-named separator to receive and expand the gas therefrom, a receiver connected to receive the partially liquefied gas from the free expansion device, a connection between the last-named separator and said receiver, including a trap, means for withdrawing liquid from said receiver, and a connection from the low pressure side of the engine to the low pressure conduit of the counter current apparatus.

90 95 100 105 28. In a gas liquefying system, means for compressing and cooling gas, high and low pressure counter current conduits, said high pressure conduit receiving the compressed cooled gas at high pressure, a separator connected to the said high pressure conduit to separate liquefied gas therefrom, a thermodynamic engine connected to receive and partially liquefy the gas from the separator, a separator connected to the outlet of the engine to separate liquid therefrom, a free expansion device connected to the last-named separator to receive and expand the gas therefrom, a receiver connected to receive the partially liquefied gas from the free expansion device, a connection between the last-named separator and said receiver, including a trap and a manually-operated valve, means for withdrawing liquid from said receiver, and a connection from the low pressure side of the engine to the low pressure conduit of the counter current apparatus.

110 115 120 125 29. In a gas liquefying system, means for compressing and cooling gas, high and low pressure counter current conduits, said high pressure conduit receiving the compressed cooled gas at high pressure, a separator connected to the said high pressure conduit to separate liquefied gas therefrom, a thermodynamic engine connected to receive and partially liquefy the gas from the separator, a separator connected to the outlet of the engine to separate liquid from the partially liquefied gas, a free expansion device connected to the last-named separator to receive and expand the gas therefrom, a receiver connected to receive the partially liquefied gas from the free expansion device, means for withdrawing the liquid from said receiver, a connection from the low pressure side of the engine to the lower pressure part of the counter current apparatus, and an envelop for the counter current conduits connected 130

to the low pressure side of the free expansion device.

30. The combination of means for compressing and cooling gas, high and lower pressure counter current conduits, said high pressure conduits connected to receive the cooled compressed gas at high pressure, a plurality of expansion devices connected to receive the gas successively, a separator for liquefied gas connected in advance of each of the expansion devices, and a return connection from the low pressure side of successive expansion devices to parts of the counter current conduits of successively lower pressure, 10 and means for withdrawing gas from each of such parts.

31. The combination of means for compressing and cooling gas, counter current conduits connected to receive the cooled compressed gas on the high pressure side, a plurality of expansion devices connected to receive the gas successively, a separator for liquefied gas connected in advance of each of the expansion devices, a connection between the high and low pressure sides of each expansion device including a trap and means for withdrawing liquid from said trap.

32. The combination of means for compressing and cooling gas, counter current conduits connected to receive the cooled compressed gas on the high pressure side, a plurality of expansion devices connected to receive the gas successively, a separator for liquefied gas connected in advance of each of the expansion devices, and a return connection from the low pressure side of successive expansion devices to parts of the counter current conduits of successively lower pressure, means for withdrawing gas from the intermediate and low pressure counter current conduits.

33. The combination of means for compressing and cooling gas, counter current

conduits connected to receive the cooled compressed gas on the high pressure side, a plurality of expansion devices connected to receive the gas successively, a separator for liquefied gas connected in advance of each of the expansion devices, and a return connection from the low pressure side of successive expansion devices to parts of the counter current conduits of successively lower pressure, means for withdrawing gas from the intermediate and low pressure counter current conduits, a receiver connected to the low pressure side of the last expansion device and means for withdrawing liquid from said receiver.

34. In a gas liquefying system, means for compressing and cooling gas, counter-current temperature interchanging means comprising high, intermediate and low pressure channels, a thermodynamic engine propelled by the compressed gas flowing through the high pressure channel of the counter current means adapted to expand the gas to an intermediate pressure, a separator adapted to receive the partially liquefied gas from the engine, an expansion device adapted to expand part of the gas from said separator from an intermediate to a low pressure, a receiver adapted to receive the partially liquefied gas from the expansion device, means for connecting the intermediate pressure separator with the intermediate pressure channel of the counter current means, and means for connecting the low pressure receiver with the low pressure channel of the counter current means.

In testimony whereof, I have hereunto set my hand at Los Angeles California this seventh day of December 1904.

GABRIEL A. BOBRICK.
